UNITED STATES PATENT OFFICE

WALTER M. RICHTER, OF STATEN ISLAND, NEW YORK

WINDOW CONSTRUCTION

Application filed January 8, 1930. Serial No. 419,224.

This invention relates to improvements in window construction, and it is the principal object of my invention to provide a window the sashes of which can be moved entirely 5 out of the window opening into a lower chamber through a trap door formed with the window sill in order to leave an unobstructed opening for moving pianos, safes, or the like furniture through the window 10 without the necessity of removing the sash cords and weights, and for facilitating the cleaning of the windows.

Another object of my invention is the provision of a window construction having a 15 removable bi-partite trap door formed in its sill normally covering the upper opening of the window receiving chamber.

Still another object of my invention is the provision of a window construction equipped 20 with means for preventing the entrance of moisture through the space between sill and window frame.

A further object of my invention is the provision of a window construction equipped 25 with a bi-partite trap door in its sill the hingedly connected parts of which are normally kept in horizontal alignment by a suitable spring controlled system of levers, adapted to be operated by a foldable operating 30 lever.

A still further object of my invention is the provision of a comparatively simple window construction, yet durable and efficient in operation.

These and other objects and advantages of my invention will become more fully known as the description thereof proceeds, and will then be specifically defined in the appended 35 claims.

In the accompanying drawing, forming a material part of this disclosure:

Fig. 1 is a front elevation of a window constructed according to my invention.

Fig. 2 is a longitudinal section on line 2—2 of Figure 1.

Fig. 3 is a side elevation of a trap door. Fig. 4 is a bottom plan view thereof on an enlarged scale.

Fig. 5 is a section on line 5—5 of Figure 3.

Fig. 6 is a section on line 6—6 of Figure 1.

Figs. 7 and 8 are detail views of means preventing moisture from entering the window.

As illustrated, a window has the usual frame 10 in which the upper and lower window sashes 11 and 12 are movably suspended for vertical reciprocation by means of the usual cords 13 guided over rollers 14.

The parts so far described are of any well known window construction and form no part of the present invention.

The sill 15 of the window is divided as at 16, and has a trap-door formed therewith composed of the parts 17, 18, carrying in their underside plates 19, 20, attached thereto, hinged together at their inner meeting ends, as at 21.

Spring arms 22, 23, are pivoted intermediate their ends to the inner face of plates 19, 20, and their ends are formed with suitable feet 24 bearing against the underside of parts 17 and 18 respectively, and engaging corresponding recesses 24' formed in the pit walls.

Near their inner ends the arms 22, 23, have pivotally attached thereto the outer ends of links 25, 26, the inner ends of which are slidably guided in suitable sockets 27, 28, secured by means of their foot plates to the underside of parts 17, 18, near their hinge 21.

To the pivot point of link 26 on arm 23 one end of a link 29 is attached, the other end of which is pivotally attached to an operating lever 30 pivoted to plate 20 at its inner end, as at 31.

Springs 32, 33, are attached at one end to the pivot point of link 25 on arm 22 and the opposite end of spring 32 is attached to the pivot point of link 29 on lever 30, while the corresponding end of spring 33 is attached to the foot of socket 27, as at 34.

The outer end of lever 30 is jointed as at 35 to the body of the lever and formed into a handle 36.

The ends of parts 17, 18 are equipped with recesses 37, 38, to engage suitable bars 39 in the window frame, and suitable tightening means 40 are provided for producing a moisture proof closure.

Similar tightening means 41 are provided in the frame attached by a chain 42 to the window.

The chamber into which the sashes are sunk 5 is arranged below the sill and designated 43 and is equipped with suitable guides 44 for the sashes.

The operation of my device will be clearly understood from the above description and 10 simultaneous inspection of the drawing. If it is desired to lower the sashes into chamber 43, lever 30 is operated to unlock the parts 17 and 18 of the sill so that the same will turn about the hinge 21 to open entrance into 15 pit and chamber 43, and the locking operation is done by a reversed order of steps.

It will be understood that I have disclosed the preferred form of my invention only and that I may make such changes therein as 20 come within the scope of the appended claims without departure from the spirit of my invention.

Having thus described my invention what I claim as new and desire to secure by Letters 25 Patent is:

1. A window construction comprising a frame, a pit formed at the lower part thereof, window sashes adapted to be lowered into said pit, a bi-partite cover for said pit constituting the window sill, hinges connecting both parts of the cover, plates on the underside of said cover parts, a system of spring controlled locking arms normally arranged on said parts, and an operating lever to operate said arms for allowing a folding of the cover parts about their hinge.

2. In a window construction, a frame, sashes therein for vertical reciprocation, a pit in the lower part of a frame, a bi-partite 40 cover for said pit having recesses in its outer ends for engaging the guide bars in said frame, and water-proofing means between said guide bars and plates in the recesses thereof.

3. In a window construction a frame, a pit formed therein, a cover for said pit composed of two parts hinged together at their meeting ends, a pair of locking arms pivotally attached to the underside of said cover, 50 links pivoted to said arms at one end and guide sockets in which the other ends of said links are displaceable, springs for controlling the movements of said arms, an operating lever connected to one of said arms, and a front end or handle jointed to the body of the lever to engage normally the front face of the pit wall.

4. In a window construction of the class described, a window frame, a pit formed in 60 its lower part, a sill, a bi-partite cover formed therewith, means for providing a moisture-proof closure for said pit, a hinge for connecting both parts of said cover, locking arms pivotally secured to the underside of said cover, and feet formed with said arms

adapted to engage recesses in the pit walls, means for normally holding said arms in their locking position to keep the cover parts in alignment, and an operating lever for withdrawing said arms from engagement with the recesses in the pit walls to allow a folding of the cover and lowering of the sashes into the pit.

In witness whereof I have signed my name to this specification.

WALTER M. RICHTER.
